WATER EDUCTOR AND METHOD

Walter T. Wells, Glendale, Calif., assignor to
The Technicraft Engineering Corporation, Los
Angeles, Calif., a corporation of California

Application July 14, 1934, Serial No. 735,212

5 Claims. (CL 166—2)

My invention relates to water eductors for flowing gas wells, and to a method of educting water therefrom and the objects of my invention are:

5 First, to provide a device of this class whereby the evacuation of water from a gas producing zone may be accomplished repeatedly without withdrawal of tubing from the well;

10 Second, to provide a device of this class which requires only a single tubing string and a packer to form a seal between the tubing string and a surrounding well casing;

Third, to provide a device of this class which may be incorporated as a unit with a packer;

15 Fourth, to provide a device of this class which incorporates means for indicating when the water level in the well has reached a level where eduction is advisable;

Fifth, to provide a novel and simple method 20 of educting water from flowing gas wells which reduces to a minimum the non-producing period of the well; and

Sixth, to provide a means and method of this class which in no manner interferes or restricts the normal production of gas.

25 With the above and other objects in view as may appear hereinafter, reference is made to the accompanying drawing, in which:

Figure 1 is a diagrammatical view of a well bore, packer, eductor, tubing string and the control means located exteriorly of the well bore; Figure 2 is an enlarged fragmentary longitudinal sectional view of the tubing string packer and eductor and surrounding casing, with parts and 30 portions shown in elevation; Figure 3 is a transverse sectional view through 3—3 of Figure 2; and Figure 4 is another transverse sectional view through 4—4 of Figure 2 with parts and portions in elevation.

35 Structures yielding a gas usually produce water which accumulates at the bottom of the well which taps the gas structure. As the water level rises and covers the gas producing structure, the flow of gas is restricted; hence it is necessary to remove the water periodically during the producing life of the well.

40 Referring to the drawing the numeral 1 indicates a well casing which leads to the gas producing formation, designated 2. A tubing string 3 is supported within the casing 1, the space therebetween is sealed off at the upper end of the casing by a plug 4 shown diagrammatically in Figure 1.

The lower end of the tubing string supports a 45 packer 5 preferably of the multiple ring type such

as set forth in my patent for Packers issued September 5, 1933, Patent Number 1,926,017. Said packer is provided with a centrally disposed tube 5a attached to a suitable collar means 5b at the upper end of the packer. A passage 5c is 5 provided between the tube 5a and the expansion and expander rings, designated 5d of the packer, a plurality of check valves 6 are mounted in the collar means 5b in such a manner as to admit gas from the lower zone, designated A through the 10 passage 5c to the upper zone designated B.

The lower end of the tubing string above the packer is provided with ports 3a. Fitted within this portion of the tubing string and within the tube 5a is a pipe 7 which is provided with a fitting 7a at its upper end adapted to form a substantially fluid tight seal therewith above the ports 3a so as to provide two additional passages through the packer. The passage designated B1 between the pipe 7 and tube 5a communicates 20 with the upper zone B through the ports 3a.

The tube 5a and pipe 7 are connected at their lower ends to close the passage B1 by a plug 8. The plug 8 supports a check or foot valve 9 adapted to admit fluid upwardly into the pipe 7. 25

A Venturi construction 10 is formed within the pipe 7 near its lower end; and a jet needle 11 is suitably supported below the venturi. Opposite the jet needle 11 the pipe 7 is provided with inwardly and upwardly directed ports 7b which 30 communicate with the passage B1.

At the mouth of the well, pipes 12 and 13 are connected with the tubing string 3 and the casing 1 respectively and are controlled by valves 14 and 15 respectively so that gas may be discharged 35 from the interior of the tubing string or zone B or both. A pressure gauge 16 may be mounted in the pipe 12 to indicate the pressure of gas therein for determining when the water level has risen so as to restrict flow therein. A compressor 17 40 is connected through a valve 18 with the pipe 13 leading to zone B of the casing. Also an auxiliary valve 19 may be provided for the tubing string for the discharge of water as it is removed from the well. 45

The eductor is operated as follows:

When the water level has encroached its permissible amount, which may be determined by gauge 16, the valves 14 and 15 are closed, valve 19 is opened and compressor 17 is started. Compressed air is delivered down zone B through passage B1 whereupon it flows upwardly with great velocity through the venturi 10 drawing water in through the valve 9 and discharging it out valve 19. After sufficient water is removed, 55

valves 18 and 19 are closed and valves 14 and 15 are opened whereupon production of gas continues.

I claim:

5. 1. A device for educting water from a flowing gas well comprising; a tubing string, a packer adapted when set to divide said well into upper and lower zones; means providing a channel for flow of liquid from said lower zone through said 10 packer and into said tubing string; means providing a conduit for fluid under pressure in said upper zone through said packer and into said tubing string, means for accumulating pressure in said upper zone and check valve means through 15 said packer normally admitting gas to said upper zone and adapted to close in response to pressure accumulation in said upper zone.
2. An apparatus for eduction of water from a gas well comprising, in combination; a well casing; a closure for the top of said casing; a packer suspended on said tubing string adapted when set to divide said casing into upper and lower zones; means within said packer providing a plurality of independent flow channels there- 25 through; means for admitting well gas and liquid from said lower zone to one of said channels; means responsive to fluid under pressure admitted from said upper zone through another of said channels, for educting said liquid so admitted upward through said tubing string; and selective means for diverting flow of gas through either said tubing string or said casing after liquid has been educted from said lower zone.
3. In a water eductor for flowing gas wells; 30 means forming a passage from the mouth to the producing zone of a gas producing well and return to said mouth; a device for circulating fluid under pressure through said means; a port at the bottom of said means communicating with

liquid in said well bore; a venturi interposed in said means and coacting with said port to educt liquid from the well upon the circulating of pressure fluid through said means; and a gas discharging conduit communicating with the gas producing region of the well incorporating said means in part and including check valves for restricting said pressure fluid from entering said gas producing region.

4. An apparatus for educting deleterious liquids from gas wells comprising: a flow channel from the gas producing zone to the surface; check valve means interposed in said flow channel to prevent return flow of fluid into the producing zone; a venturi ejecting device suspended in 15 said flow channel at a level to act upon deleterious fluids encroaching on the producing zone; a pressure fluid intake communicating between said device and a point in said flow channel above 20 said check valve means; and a discharge line 25 communicating directly between said device and the mouth of the well.

5. An apparatus for educting deleterious liquids from gas wells comprising: a flow channel from the gas producing zone to the surface; a 25 packer interposed in said channel above the producing zone and incorporating check valve means to prevent application of back pressure in said channel from being applied against the producing zone; a venturi ejecting device suspended in said flow channel below said packer and positioned at a level to act upon deleterious fluids encroaching on said producing zone; a pressure fluid intake communicating between said device and a point in said flow channel above said packer; and a 30 discharge line communicating between said device and the mouth of the well.
